US00D936979S

(12) **United States Design Patent** (10) Patent No.: **US D936,979 S**
(45) Date of Patent: **** Nov. 30, 2021**

(54) **HANGER**

(71) Applicant: **TARGET BRANDS, INC.**,
Minneapolis, MN (US)

(72) Inventors: **Laurie Losness**, Coon Rapids, MN
(US); **Richard P. Riedel**, Blaine, MN
(US); **Terrence J. Hornsby, Jr.**,
Minneapolis, MN (US)

(73) Assignee: **TARGET BRANDS, INC.**,
Minneapolis, MN (US)

(**) Term: **15 Years**

(21) Appl. No.: **29/712,577**

(22) Filed: **Nov. 8, 2019**

(51) LOC (13) Cl. **06-08**

(52) U.S. Cl.

USPC **D6/315**; D6/328

(58) **Field of Classification Search**

(57) CLAIM

The ornamental design for a hanger, as shown and described.

DESCRIPTION

FIG. 1 is a front, top perspective view of a hanger showing a first embodiment of our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof.

FIG. 8 is a front, top perspective view of a hanger showing a second embodiment of our new design;

FIG. 9 is a front view thereof;

FIG. 10 is a rear view thereof;

FIG. 11 is a right side view thereof;

FIG. 12 is a left side view thereof;

FIG. 13 is a top view thereof; and

FIG. 14 is a bottom view thereof.

FIG. 15 is a front, top perspective view of a hanger showing a third embodiment of our new design;

FIG. 16 is a front view thereof;

FIG. 17 is a rear view thereof;

FIG. 18 is a right side view thereof;

FIG. 19 is a left side view thereof;

FIG. 20 is a top view thereof; and

FIG. 21 is a bottom view thereof.

FIG. 22 is a front, top perspective view of a hanger showing a fourth embodiment of our new design;

FIG. 23 is a front view thereof;

FIG. 24 is a rear view thereof;

FIG. 25 is a right side view thereof;

FIG. 26 is a left side view thereof;

FIG. 27 is a top view thereof; and

FIG. 28 is a bottom view thereof.

FIG. 29 is a front, top perspective view of a hanger showing a fifth embodiment of our new design;

FIG. 30 is a front view thereof;

FIG. 31 is a rear view thereof;

FIG. 32 is a right side view thereof;

FIG. 33 is a left side view thereof;

FIG. 34 is a top view thereof; and

FIG. 35 is a bottom view thereof.

FIG. 36 is a front, top perspective view of a hanger showing a sixth embodiment of our new design;

FIG. 37 is a front view thereof;

FIG. 38 is a rear view thereof;

FIG. 39 is a right side view thereof;

FIG. 40 is a left side view thereof;

FIG. 41 is a top view thereof; and

FIG. 42 is a bottom view thereof.

FIG. 43 is a front, top perspective view of a hanger showing a seventh embodiment of our new design;

FIG. 44 is a front view thereof;

FIG. 45 is a rear view thereof;

FIG. 46 is a right side view thereof;

FIG. 47 is a left side view thereof;

FIG. 48 is a top view thereof; and,

FIG. 49 is a bottom view thereof.

The features shown in broken lines are portions of the hanger forming no part of the claimed design. The features shown in long dash-short dash bolded broken lines indicate the bounds of the claimed design and otherwise form no part of the claimed design.
